[57] CLAIM

The ornamental design for a dressage girth cover, as
shown and described.

DESCRIPTION

FIG. 1 is a perspective view of a dressage girth cover
showing my new design;

FIG. 2 is a top plan view thereof;

FIG. 3 is a side elevational view thereof; the opposite
side being a mirror image of the side shown;

FIG. 4 is a bottom plan view thereof;

FIG. 5 is an end elevational view thereof; and,

FIG. 6 is a bottom plan view with the straps and buckles
removed for illustration.

The broken line representation of a horse and saddle
with dressage straps and buckles in FIG. 1 and the
straps and buckles in FIGS. 3, 4 and 5 are for illustrative
purposes only and form no part of the claimed design.
